UNITED STATES PATENT OFFICE

2,370,436

GARMENT HANGER

Frank Zimmerman, Detroit, Mich.

Application September 16, 1944, Serial No. 554,465

1 Claim. (Cl. 223—91)

The present invention relates to new and useful improvements in garment hangers and has for its primary object to provide means carried by the hanger for clamping a skirt or a pair of trousers thereto.

A further important object of the present invention is to provide attaching means for a skirt or trousers clamping member and adapted for attaching to a conventional form of wooden or metal coat hanger without necessitating any changes or alterations in the construction of the hanger.

A still further object is to provide an attachment of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a front elevational view of the hanger showing the attachment in position thereon.

Figure 2 is a plan view of the blank of sheet metal forming the attaching means for the skirt or trousers clamping member, and

Figure 3 is a sectional view taken substantially on a line 3—3 of Figure 1.

Referring now to the drawing in detail wherein for the purpose of illustration I have disclosed a preferred embodiment of the invention, the numeral 5 designates a wire coat hanger of conventional construction and which includes the inclined shoulder portions 6 and the lower horizontal hanger bar 7.

A light gauge sheet metal plate 8 of generally elongated construction is formed at its upper edges with a pair of tongues 9 and formed at its lower edges with tongues 10 adjacent each end thereof and with an intermediate tongue 11, the

tongues 9 being adapted for bending over the shoulder portions 6 of the hanger, while the tongues 10 and 11 are adapted for bending over the hanger bar 7 to secure the plate 8 in position thereto as shown in Figure 1 of the drawing.

A pair of ears 12 are struck from the plate 8 adjacent each end thereof, the ears at the respective ends of the plate being bent outwardly in spaced parallel relation and formed with openings 13 adapted for pivotally receiving the in-turned ends 14 of a substantially U-shaped clamping bar 15 adapted for clamping engagement against one surface of the plate 8. Mounted on the inturned ends 14 of the clamping member is a coil spring 16 having one end 17 bearing against the plate 8 while the other end 18 of the spring bears against one leg of the clamping member 15, to thereby yieldably urge the clamping member into clamping engagement against the plate for holding a skirt or pair of trousers on the hanger.

The intermediate portion of the clamping member 15 is formed with an upwardly offset portion 19 to provide a finger grip to facilitate gripping of the clamping member to release the garment.

It is believed that the details of construction and manner of use of the device will be readily understood from the foregoing without further detailed explanation.

Having thus described the invention, what I claim is:

An attachment for a garment hanger of a type including inclined shoulder portions and a horizontal hanger bar, an elongated rigid plate, tongues formed on the edges of said plate adapted for bending over the shoulder portions and horizontal bar of the hanger for securing the plate horizontally thereon, and a spring actuated clamping member pivotally carried by the plate and adapted for clamping a garment against the plate.

FRANK ZIMMERMAN.
